(57) **CLAIM**

The ornamental design for a pet water dispenser, as shown and described.

DESCRIPTION

FIG. 1 is a top perspective view of a pet water dispenser design showing my new design.

FIG. 2 is a bottom perspective view of the pet water dispenser.

FIG. 3 is a front view of the pet water dispenser.

FIG. 4 is a rear view of the pet water dispenser.

FIG. 5 is a left view of the pet water dispenser.

FIG. 6 is a right view of the pet water dispenser.

FIG. 7 is a top view of the pet water dispenser.

FIG. 8 is a bottom view of the pet water dispenser.

FIG. 9 is an enlarged view of FIG. 1; and,

FIG. 10 is an enlarged view of FIG. 8.

The broken lines in the drawings depict portions of the pet water dispenser that form no part of the claimed design.
